MACHINE AND METHOD OF MAKING BAGS

Eino E. Lakso, Fitchburg, Mass., assignor, by
mesne assignments, to Owens-Illinois Glass
Company, Toledo, Ohio, a corporation of Ohio
Application April 28, 1936, Serial No. 76,778

33 Claims. (Cl. 93—18)

This invention relates to apparatus and method of making bags from sheet material in web form, and more particularly to the advancing, assembling and sealing together of a plurality of the webs.

The apparatus and method hereinafter described more in detail is adapted particularly for making a bag of the type disclosed in the C. W. Vogt Patent 2,171,717, issued September 5, 1939, in which the web section forming one wall of the bag is longer than that forming the opposite wall, and the excess material is folded to form a pleat which may be opened along its fold line and serve for filling or as a dispensing

15 spout.

It will be obvious that although certain features of the invention relate particularly to the means employed for forming said pleat, other features are useful and important in forming a bag which does not have such a spout.

In carrying out my invention a plurality of webs is brought into juxtaposition and sealed together along opposite edges to form a collapsed bag preferably with infolded sides and preferably sealed across both ends, so that the resulting bag is sealed shut in collapsed condition and so that the interior will be protected against any contamination during shipment and storage prior to filling.

20 As one important feature of the invention the sealing is effected by the application of heat and pressure, and this sealing may be effected either with or without the use of a separate adhesive, depending upon the character of the material used. There is preferably employed a sheet material such for instance as that made of a chlorinated rubber compound and sold under the trade name "pliofilm," layers of which may be sealed together by the application of heat and pressure and without the need of any other adhesive.

25 The sealing is effected in such a way that the contents of the bag when the latter is filled is not exposed to the adhesive, if such be employed.

30 As a further feature means are employed for infolding the side walls of the bag to form the latter in a flat state and to seal the ends and sever the collapsed bags in the sealed condition.

As a further feature means are employed for substantially completely removing or excluding air from the interior of the bag prior to the sealing.

35 As a further feature means are employed for giving a relatively longer contact period of the heat sealing elements across the ends where there is additional thickness due to the infolding of the sides.

40 As a further important feature means are employed for imparting an initial or secondary sealing operation transversely of the bag in or-

der to locate the position of the spout or other filling or dispensing opening during the advancing of the webs.

As a further feature means are provided for sealing the seam underneath the spout prior to the main sealing operation.

The invention involves various other important features and many important advantages which will be apparent from a consideration of the specific form hereinafter described or will be pointed out in the description.

Reference is to be had to the accompanying drawings illustrating a machine embodying my invention and adapted for carrying out my improved method, said drawings also illustrating an alternative form in which certain of the features may be embodied.

In these drawings:

Fig. 1 is a side elevation of a machine with the rolls of the webs employed in position, 20

Fig. 2 is a vertical longitudinal section of the main portion of the machine and on a somewhat larger scale,

Fig. 3 is a view similar to Fig. 1, but showing the opposite side of the machine and on a 25 slightly larger scale than Fig. 1,

Fig. 4 is a transverse section on the line 4—4 of Fig. 2.

Fig. 5 is a horizontal section on the line 5—5 of Fig. 2, certain of the parts being broken away, 30

Fig. 6, 7 and 8 are vertical transverse sections on the lines 6—6, 7—7 and 8—8 respectively of Fig. 5,

Fig. 9, 10, 11 and 12 are vertical transverse sections on the lines 9—9, 10—10, 11—11 and 35 12—12 respectively of Fig. 2,

Fig. 13 is an enlarged transverse vertical section similar to a portion of Fig. 12, the upper rotor being in elevation,

Fig. 14 is an enlarged vertical longitudinal 40 section taken on the line 14—14 of Fig. 12, but showing the heated lugs of the spot sealer advanced approximately 20° from the position shown in Fig. 2,

Fig. 14a is a fragmentary diagrammatic view 45 showing the impressions made by the spot sealing lugs and scoring bar shown in Figs. 13 and 14,

Fig. 15 is a vertical longitudinal section similar to Fig. 14, but with the spot sealer advanced approximately 180° from the position shown in 50 Fig. 2,

Fig. 16 is a vertical transverse section through the seam sealing mechanism, the bag severing mechanism and parts of the driving mechanism, said section being taken on the line 16—16 of 55 Fig. 2,

Fig. 17 is a view similar to a portion of Fig. 16, but on a larger scale and showing the seam sealing roller and forming anvil with the tube in place, 60

- Fig. 18 is a sectional detail on the line 18—18 of Fig. 17.
- Fig. 19 is a section on the line 19—19 of Fig. 2 and showing the pull rollers.
- Fig. 20 is a sectional detail similar to a portion of Fig. 19, but on a larger scale.
- Fig. 21 is a view similar to a portion of Fig. 2 and showing further details of the cross sealing mechanism.
- Fig. 22 is an end elevation of a portion of the mechanism shown in Fig. 21.
- Fig. 23 is a sectional detail on a larger scale taken on the line 23—23 of Fig. 21.
- Fig. 24 is a fragmentary diagram of the tube showing the relative positions of the cross sealing, the spot seals and the spout forming pleat.
- Fig. 25 is a perspective view of the completed sealed bag after severance along the dot and dash line shown in Fig. 24 and with the pleat partially distorted.
- Fig. 26 is a view similar to a portion of Fig. 2, but showing other and additional features which may be employed.
- Fig. 27 is a section on the line 27—27 of Fig. 26.
- Fig. 28 is a detail in plan of certain of the parts shown in Figs. 26 and 27, and
- Fig. 29 is a fragmentary diagram of a portion of the web cut by the mechanism shown in Figs. 26, 27 and 28.
- The operating parts and the material to be operated upon are supported by a main frame which for convenience of manufacture may include a sub-base 30, a main base 31 and a pair of side frames 32. These may be rigidly secured in any suitable manner. The main base at one end carries a pair of bracket arms 35 adapted to support the mandrel or arbor 37 for a roll A of web material such as "pliofilm" or other heat sealing material and which may be a single ply of the material or may be laminated or coated.
- Carried by the main frame 31 there is a pair of brackets 38 and 39 connected together at their upper ends by a cross bar 40. The bolts 41 which connect the brackets to the cross bar may be shouldered and held in place by nuts 42 and they serve as arbors or mandrels for a pair of rolls B and C. The rolls may be held against endwise movement by collars or flanges 43 on the outer or free ends of the mandrels. The roll B is of "pliofilm" or other heat sealable material, while the roll C is of non-heat sealable material such as paper. The web material on the roll C, when used in making the specific bag hereinafter described, may be somewhat wider than the material on the roll B.
- Any suitable means may be employed for preventing the free rotation of the rolls A, B and C, but permitting the rotation upon the proper pull on the material. Merely as an example, I have shown a brake for preventing free rotation of the roll A. This includes a pair of curved clamping brake members or shoes 44 and 45 bearing upon a drum 46 secured to the arbor 37 so as to rotate therewith. The shoes 44 and 45 are pressed together by a spring 47, the tension of which may be adjusted by rotation of the threaded stud 48. One of the brake shoes may have an extension pressed against a stop 50 on the bracket 35 so that the brake shoes cannot rotate with the drum.
- By control of the compression of the spring 47, the desired amount of drag may be imparted to the brake mechanism.
- For preventing free rotation of the rolls B and C cross head slides 51 may be mounted on the cross bar 40 and each slide may be provided with

a pin 52 engaging the periphery of the corresponding roll of material. The slides may be connected to weights 53 by flexible cords 54 passing over grooved pulleys 55.

Mechanism is provided for withdrawing the web material from the three separate rolls, bringing the webs into superposed relationship, and sealing them together to form the tube which is cut into sections to form the bags.

The web delivered from the roll A is very much wider than the webs delivered from either of the other two rolls, and is employed to form not only one flat side of the bag, but also the two opposed infolded sides. This web is delivered over a roller 56 (see Fig. 2) carried by extensions of the side frames 32, and then passes beneath the mechanism which brings together the other two webs and forms the tuck or pleat which is to become the spout of the bag. After passing over the roller 56 it is progressively formed into a substantially U-shaped or trough-like contour by a forming shoe 59 which is supported by the underside of a plate 60 resting upon the upper flanged sides of the frame members 32. In order to maintain proper alignment of this forming shoe or mandrel, the plate 60 is provided with a groove 61 (see Fig. 9) into which the upper side of the mandrel or shoe is fitted.

The shoe or mandrel 59 beyond its point of support is provided with a pair of fingers 62, 62 which serve to turn the upper edges of the channel-shaped web inwardly (Figs. 5 and 6). The fingers are provided with depending guard plates 63, 63 which hold the web A in sliding relationship with the outer opposite sides of the shoe or mandrel 59.

The web A in U-shape and with inwardly turned upper margins advances along the shoe to the opposite end of the latter and there the opposite parallel upwardly extending side walls engage with fingers 64, 64 (Fig. 7) mounted on supports 65 carried by a cross bar 66 secured to the side frame members 32. These fingers fold inwardly the side walls of the channel-shaped web progressively as the latter advances, and thus progressively bring the upper inturned edges and the flat bottom of the channel-shaped web nearer together and eventually into directly superposed relationship.

The fingers 64, 64 may be at the same elevation if the bag to be made is square or is rectangular with the width greater than the height, viewing the tube in the position in which it is being produced to form the bag. If the tube is to be of greater height than width, then the tucker fingers should be at slightly different elevations as indicated in Fig. 7 so that they will cause the two infolded pleats to overlap rather than directly abut.

The web in this folded condition and with the other sheets applied thereto as hereinafter described passes around a drum 67 and is pulled at a uniform speed by a pair of driven gripping rollers 68, 69.

The non-heat sealable material hereinafter referred to as the web C passes around a guide pin or roller 70 and thence around a roller 71 which preferably is provided with a layer 72 of compressible material, such as rubber. This roller 71 is mounted on a shaft 73 driven by a gear 74 meshing with a gear 75 (Fig. 3) on the shaft 77 of a glue roller 76 mounted in a glue pot 78. The surface of the glue roller is preferably provided with cross scores or knurls a few thousandths of an inch deep and closely spaced so

that when the glue roller is rotated the major portion of the glue may be scraped from the periphery by means of a conductor bar 79 leaving only sufficient glue to fill the cross grooves or knurls.

By the term "glue" I mean to include any form of adhesive which may properly secure together the webs B and C.

Suitable means are provided whereby the delivery of glue to the surface of the web C may be prevented when the machine is being threaded up or when it is stopped. Any suitable means may be employed for this purpose, but that shown involves the use of a movable glue pot with the glue roller 76 carried thereby. As shown the shaft 77 of the glue roller is mounted on the walls of the glue pot and the glue pot is mounted to slide horizontally to bring the glue roller into or out of engagement with the sheet passing around the roller 71. For moving the glue pot there is provided an eccentric 81 (Figs. 2 and 4) mounted on a shaft 82 which latter is journaled in extensions of the side frames 32. An eccentric strap 84 encircles the eccentric and is connected to an adjustable forked link 85 which may detachably engage a pin 86 carried by lugs on the end of the glue pot. By rotating the shaft 82 by means of a handle or pin 83 the pressure of the glue roller against the web C may be varied, or the glue roller may move entirely out of engagement with the web. It is not essential that any large range of movement be provided and in fact it need not be so great as to move the gear 75 out of engagement with the gear 74. If it is desired to remove the glue pot and its roller from the machine, the link 85 may be swung out of engagement with the pin 86, thus completely freeing the glue pot.

The web C, after receiving the coating, layer 40 or narrow strips of adhesive, is brought into surface contact with the web B and the two pass together around the idler roller 37, whereby a laminated sheet is formed. This idler roller may be slightly shorter than the width of the web 45 B, and the latter, as previously noted, may be slightly narrower than the web C. Thus any adhesive on the marginal edges of the web C will not come in contact with the roller 37.

not come in contact with the roller 88. The laminated web B—C then passes over a driven roller 88 which preferably has a rubber or other readily compressible facing layer 89. This roller 88 is mounted on a shaft 90 having a driving bevel pinion 90a (Fig. 3) secured thereto. Beneath and closely adjacent to this roller 88 there is provided a grooved roller 91 (Figs. 2 and 11) mounted for free rotation within the mandrel or forming shoe 59 and adjustable toward and from the roller 88. As shown particularly in Fig. 11 the walls of the mandrel carry a pin 92, the end portions of which are eccentric whereby upon rotating the pin the axis may be moved toward and from the axis of the roller 88. The roller 91 is rotatable upon this normally stationary pin 92 by ball or other substantially frictionless bearings. By means of the eccentric the spacing between the rollers 91 and 88 may be adjusted in accordance with the thickness of the laminated web B—C passing therebetween.

The groove 91a in the periphery of the roller 91 serves to receive a finger on the end of a plate 93 secured to the top of the mandrel 59 and serving to strip the laminated web B-C from the roller 91 and cause it to pass over said plate. The opposite edges of this plate are undercut as shown particularly in Fig. 8 so that

the inturned edges of the sheet A may pass therebeneath and slightly spaced from the laminated web B-C. The relative widths of the webs B-C and of the channel-shaped web A will also be apparent from this figure.

The plate 93 is of approximately the same width as the web B and the marginal edge portions of the plate 93 prevent the edge portions of the web C which have adhesive on the under side from directly contacting with the inturned edges 10 of the channel-shaped web A.

The laminated web B—C is maintained in flat position as it advances from the roller 88 by means of a plate 94 (Fig. 8) mounted on a shoe 95 which in turn is mounted on a cross bar 96 15 carried by one of the side frames 32 (Fig. 5). The shoe may be slid lengthwise along the cross bar and away from the sheets to facilitate the threading up of the machine, particularly with the laminated web B—C. When in operative 20 position, as shown in Figs. 5 and 8, it is held against endwise movement by any suitable centering device, such for instance as a pointed plunger 97, pressed down by a spring and adapted to enter a depression or socket at the predetermined point on the upper side of the bar 96. 25

The outer peripheral speed of the roller 88 is somewhat greater than the peripheral speed of the rollers 68 and 69 which advance the combined webs A, B and C, and therefore the laminated web B-C is advanced at a faster rate than the web A. As a result of this faster travel there is a periodic accumulation of the laminated web B-C in the form of a loop. Each loop as formed is flattened or folded down to make the pleat on the bag wall and which serves as the spout. 30 35

In order to predetermine the location of the loops the laminated web B-C is first brought in contact with and firmly secured to the in-turned edges of the web A at spaced points. For accomplishing this result there is provided the mechanism shown in Fig. 2 and more particularly in Figs. 12 to 15.

Above the laminated web B-C there is provided a rotor 98 having two peripherally extending lugs constituting heater shoes 99 in transverse alignment for pressing localized areas of the laminated web B-C to the under web A, these areas being adjacent to opposite edges of the webs and indicated at 99c in Fig. 14a. The rotor 98 has a heating element 100 which may be provided with electric conductors which will deliver current to the heating element through the rotation of the latter. Merely as an example of such electric conducting means, I have shown the heating element in Fig. 12 as provided with conductors 101 leading to separate collector rings 102 which are engaged by brushes 103, these brushes being connected to the opposite terminals of a suitable source of electrical energy.

This rotor 98 with its shoes constitutes a spot sealer and is rotatably mounted upon a pair of stub shafts 104, 105 and is rotated by means of a pinion 106. The spot sealer may be vertically 65 adjusted by mounting the stub shafts in bearings 107 which may be forced downwardly to the desired extent and against the action of springs by adjusting screws.

Directly beneath the spot sealer there is provided cooperating means against which the laminated webs are pressed by the heated lugs 99 and which also cooperates in forming a score line in the laminated web B-C intermediate of the edges of the latter. As shown particularly in 75

Fig. 13 the forming shoe 59 is provided with a shaft 108 journaled in a pair of ball bearings 109 and provided at its ends and on the outer sides of the shoe 59 with a pair of rollers 110. 5 These may be held in place upon opposite ends of the stub shaft by screws 111. At the center of the shaft and between the ball bearings there is provided a roller 112 which has an annular compressible ring 113. This may be secured in 10 place in any suitable manner, as for instance by means of bevel faced washer 114 and rivets 115.

The rollers 110 are provided with similar compressible peripheral rims or collars. As the spot 15 sealer may be adjusted toward and from the rollers 110 the lugs may be caused to press the laminated web against the inturned edges of the web A to bring the superposed heat sealable materials A and B into direct contact with the proper 20 amount of heat and the proper amount of pressure to firmly bond them together, and the heated shoes 99 will be prevented from direct contact with the "pliofilm." The result of this spot sealing is to connect the three webs together at points 25 adjacent to opposite edges and spaced apart to distances equal to the peripheral path of the end surfaces of the heating lugs 99. As previously noted two such spot sealed areas are indicated at 99c in Fig. 14a.

30 The rotor 98 is also provided with means for scoring the upper web B-C transversely along lines spaced apart along the length of the web. The two lugs 99 carry a transverse scoring plate 116 which has a section of its outer edge substantially in alignment with one side of the two lugs and so positioned that it will press against the annular compressible ring 113 and form a score line 116a shown in Figs. 14a. This score line is in transverse alignment with the advance 35 ends of the spot sealed portions, and facilitates the bending of the laminated web B-C into loops at a predetermined position as hereinafter described.

Beyond the spot sealer there is provided a roller 118 which is free to move vertically to a slight 45 extent in respect to a flat surface of the forming shoe 59 as the loop is pressed down to form a pleat. It serves, by its own weight, to press the laminated web B-C downwardly and prevent any accumulated excess material from passing 50 therebeneath at any different rate than that of the channel shaped web A. The loop pressing roller 118 preferably has annular flanges on its ends (Fig. 5). Its position may be adjusted along 55 the path of movement of the webs in accordance with the desired height of the pleat to be formed. As shown in Fig. 15 a loop in the laminated web B-C may gradually form while the spot sealing lugs 99 are traveling through the upper portion 60 of their path of movement, and this loop will gradually increase in height until the spot sealing lugs act to press the webs together and onto the rollers 110. At that time the loop will have reached substantially the shape shown in Fig. 14. 65 As the webs have been spot sealed together and as the upper web has been transversely scored, the continuation of the material will cause the accumulated loop to narrow up to a pleat and this pleat to be folded over upon the score line 116a, and as shown at the right of Fig. 15. As 70 soon as the pleat has passed beneath the roller 118, another loop will begin to form and will increase until the spot sealer again connects together the layers, and the next accumulated 75 loop will be laid down as another pleat. The

rate of travel of the materials, the amount of material in each loop, and the spacing of the loops along the length of the tube will be proportional to the length of the desired bag and the width of the desired pleat for each bag.

5 After passing under the roller 118 whereby the folded pleat is formed, the three superposed webs pass to mechanism which forms the continuous seals along the opposite edges and between the webs A and B. The spot sealer hereinbefore described seals only those portions of the side edges which lie beneath the pleat, and which therefore would not be as readily heated and sealed by the application of heat and pressure through the pleat. The continuous side sealers 10 15 are shown particularly in Figs. 16, 17 and 18 and the position is indicated in Figs. 2 and 5.

The gear 106 of the spot sealer meshes with a driving gear 120 which latter also drives a gear 121 of the seam sealer. This seam sealer is 20 very similar in many respects to the spot sealer except that it makes continuous seals rather than spot seals and does not make any transverse score line. The upper element of the seam sealer includes a rotor 119 mounted on the stub shaft 25 123 as well as on a stub shaft 122 in alignment therewith and supporting the gear 121. The rotor 119 has annular flanges at the ends serving as the pressing elements, and these are heated by an annular heating element encircling the 30 rotor 119 between said end flanges. The means for conducting the current to the heating element is indicated in Fig. 16, but need not be described as it may be substantially identical with that employed in conducting heat to the spot 35 sealer as shown in Fig. 12.

The peripheral surfaces of the two annular flanges of the rotor 119 may be grooved to concentrate the heat and pressure along a pair of narrow lines rather than along a wider area.

40 Below the rotor 119 there is provided a co-acting element which may be similar in all respects to that shown in Fig. 13 except that the center part coacting with the scoring blade may be omitted. This is illustrated in Fig. 17 and 45 it is thought that detailed description is unnecessary in view of the description of the construction shown in Fig. 13.

Below the rotor 119 there is provided a co-acting element which may be similar in all respects to that shown in Fig. 13 except that the center part coacting with the scoring blade may be omitted. This is illustrated in Fig. 17 and 45 it is thought that detailed description is unnecessary in view of the description of the construction shown in Fig. 13.

For driving the spot sealer and seam sealer the shaft of the gear 120 may be provided with a 50 bevel pinion 124 meshing with a bevel pinion 125 on a vertical drive shaft 126 supported in brackets 127 and 128 on one of the side frames as shown in Figs. 3 and 16.

The machine may be readily threaded up without lifting the spot sealer as the machine may be stopped with the sealing lugs in an upward position, but as the sealing surfaces of the rotor 119 are continuous it is desirable to provide means for lifting this element and holding it in raised position during threading up or when the machine is stopped, to prevent overheating of the webs therebeneath. As shown particularly in Fig. 2 the lifting means includes a lever 129 fixed to a shaft 130 mounted in bearings on the cross 60 bar 66 which as previously noted also carries the tucker members for the side walls of the advancing tube. An upwardly extending lever arm fixed to the shaft 130 is connected by a pin 132 to a locking lever 134 which lever has a depending lug 70 135 movable into or out of engagement with the side of the bar 66 opposite to the shaft 130. The lever 134 is normally in raised position as shown in Fig. 2, and the lever 129 is swung counter-clockwise by a spring 133 so as to hold the seam 75

sealer in lowered position, the shaft of the seam sealer being mounted in the substantially horizontal arms of said bracket. By pressing down on the outer free end of the lever 134, the lug 135 will ride down onto the outer side of the bar 66, thereby rotating the shaft 130 in a clockwise direction and compressing the spring 133. When the lever 134 reaches its lower limiting position, its engagement with the bar 66 will prevent the return movement of the lever 129, and the seam sealer will be locked in raised position. To return it to operative position it is merely necessary to lift the outer end of the lever 134.

As the superposed webs pass beneath the flanges of the heated rotor 119 they likewise pass over the ends of the pleat F, and the application of the heat and pressure, weld, fuse or cement the "pliofilm" web B to the inturned edges of the channel-shaped web A and form a continuous tube in extended condition and around the mandrel or shoe 59. As this tube passes beyond the end of the mandrel, the tuckers 64 press in the intermediate portions of the side walls of the tube, and the height of the tube is gradually decreased until it is in fully collapsed or flattened condition. The tube reaches this condition as it comes tangential to the drum 67, and as it passes around the drum, all of the air is squeezed out. To make the infolding a more gradual operation, and therefore easier, the tuckers may be longer and the drum 67 spaced to a greater distance from the side sealers than is shown in the drawings.

While the flattened or collapsed tube is passing around the drum 67, a sealing mechanism comes into operation which seals the tube transversely at spaced points along the length thereof. As shown particularly in Fig. 2, the drum is rotatably mounted on a fixed shaft 136, and on the periphery of the drum are compressible pads 138 preferably of rubber and mounted in dove tailed grooves. The periphery of the drum is the multiple of a length of a completed bag in collapsed condition and the pads are therefore spaced at equal distances apart, the arcuate distance being the length of an individual collapsed bag.

On the shaft 136 of the drum 67 there are provided sprocket wheels 139 which engage a pair of endless chains 141 carrying cross seam sealers 140. These seam sealers are spaced apart along the length of the chain so as to register in succession with the successive compressible pads 138. Each seam sealer is provided with a pair of rollers 142 carried by a saddle casting 143 and each includes an electric heating element 144. In order to control the amount of heat rendered applicable for the sealing operation, each sealing element is connected in series with a heat control element 145 as shown particularly in Fig. 23. This serves to break the electric circuit when the heat sealer has reached the desired temperature, and to close the circuit when the temperature drops below the predetermined point.

Each heating element and its control element has terminals connected to brushes riding on the periphery of collector plates 146. The collector plates conform in contour to the general path defined by the chain, and the current is delivered to one of these plates and taken off from the other in any suitable manner. As the plates are outside of one of the sprockets, it is preferable to provide the sprockets with recesses through which the connections may extend while the chain is in contact with the sprockets.

In order to insure proper and intimate pres-

sure contact of the heated sheet across the collapsed tube at the area corresponding to that of the pad 138, there is provided a guide member 147 with a curved surface substantially concentric with a portion of the periphery of the drum and along which the rollers 142 may travel while pressing the heater against the tube. This guide member may be carried by a pair of shafts 150 supported in a bracket 151. The guide may be directly secured to the lower shaft and to a plate 149 secured to the upper shaft 150. The sprockets are rotatably mounted on the ends of these shafts. By placing one or more shims between the guide member 147 and the plate 149, the placing of the guide member in respect to the drum may be varied to give the desired pressure of the heating element against the tube on the pad 138. The adjustment may be secured in various other ways, for instance by adjusting the bracket 151.

Preferably each cross heater 140 is provided with recesses 140a upon opposite sides, as shown particularly in Fig. 22, and which serve to form corresponding relief portions on the cross seals at their centers to prevent strain. These relief portions serve to produce bags which are less likely to leak due to internal pressure when they have become filled, due to the distribution of strain where the infold joins the cross seal.

To drive the drum 67 the shaft of the latter is provided with a gear 154 which meshes with a pinion 152 (Fig. 1) on a transverse shaft 153. The latter is provided with a bevel driving pinion 153a (Fig. 3). By this drive the drum is rotated and advances with the tube while clamping the latter tightly against the outside of the drum and the collapsed tube is delivered between the pull rollers 68 and 69.

If the infolded portions of the side of the tube overlap as previously indicated, the feed roller 68 is provided with a peripheral groove to accommodate for the increased thickness as indicated in Figs. 19 and 20. The roller 68 is mounted on a shaft 155 which is provided with a pinion 155a and is mounted in a bracket or housing 156 secured to one of the side frames 32 (Fig. 19). The pinion 155a meshes with the pinion 157a on the shaft 151 supporting the lower pull roller 69. This last mentioned shaft has a gear 158a which is driven by the cutter mechanism which subdivides the tube into successive sections and intermediate the opposite side edges of each cross seal. As shown it meshes with the gear 158a on a shaft 158, and the latter has a bevel pinion 160 meshing with a bevel pinion 200 on the vertical shaft 126 which drives the side seam sealers as shown in Fig. 16.

The shaft 158 also carries a sprocket 161, a cutter head 162, a sprocket sleeve 163, a collar 164, a clutch member 165 and a hand wheel 166 (Fig. 16). The clutch serves for disconnecting the operating parts of the machine from the source of power and permits the machine to be readily turned over by hand. By disengaging the clutch, the machine may be turned over without turning over the motor reducing gears, as will be more fully explained hereinafter.

The cutter head 162 which is mounted on the shaft 158 is provided with a rubber insert 167 which is notched out for mounting a knife 168 which is firmly but adjustably attached to the cutter head and locked by means of a gib 169 (Fig. 16). The rubber insert serves to feed the tube after leaving the pull rollers 68 and 69.

The pinion 158 on the shaft 158 meshes with

a pinion 170 on a shaft 171 which carries the lower roller 173 cooperating with the cutter head. This roller is provided with a knife block 174 mounted in the periphery so as to oppose the cutting edge of the knife 168 at the point of severance of the tube. Any other suitable form of transverse cutting mechanism may be employed for subdividing the collapsed tube into completed bags. The shaft 171 carries a bevel pinion 175 which drives the shaft 202.

A second pair of feed rollers are provided for delivering the successive completed bags from the machine after they are severed, and this delivery mechanism is preferably designed to advance the bags at a higher rate of speed than that of tube formation. As shown particularly in Fig. 2 the frame of the machine supports a pair of shafts 176, 177, the first mentioned shaft having a sprocket 178, a gear 179 and a segmental roller 180. On the rear end of the shaft there is provided a worm 181. The sprocket 178 is connected with the sprocket 161 on the shaft 158 by means of a chain 182. The sprockets 178 and 161 are of the same diameter, and therefore the two shafts 158 and 176 will turn with the same number of revolutions per minute, but the distance from the center of the shaft 176 to the line of bag travel is greater than the distance from the center line of the shaft 158 to the line of tube travel. The segmental roller 180 comes into engagement with the bag at substantially the instant at which the bag is severed from the tube, and due to the greater radius of this segmental roller the bag when severed will be advanced at a faster speed than that of tube formation and until the bag moves out of contact with this roller.

Cooperating with the segmental roller 180 is a lower supporting roller 183 which is mounted on the shaft 171. This roller preferably has a rubber or other yielding surface, and its shaft is provided with a pinion 184 meshing with the gear 179 on the shaft 176. The action of the segmental roller 180 and the supporting roller 183 gives to the severed bag such an acceleration that the bag will travel onto a take-off or stacking conveyer. To prevent the bag from being thrown too far there may be provided a guard 185 (Fig. 3). Any convenient means may be provided for driving the take-off conveyer. Merely as an example I have shown the conveyer being driven through the worm 181 on the shaft 176. A worm wheel 186 engages this worm and is fixed to a vertical shaft journaled in a bracket 187 on the frame 32. The lower end of the shaft is provided with a worm 188 engaging a worm wheel 189 on a shaft 190 which latter is provided with a pair of belt pulleys 191 and endless belts 192 constituting the take-off conveyer. These belts may be of any desired length depending on the location of the station upon which the bags are to be delivered.

Power may be delivered to the machine in any suitable manner. For instance, a motor 193 may be mounted beneath the main frame 31 and provided with a Reeves variable speed drive or other suitable speed varying mechanism 194 and from the latter through a speed reducer 195 and thence by a sprocket 197 and chain 198 to the sprocket 199 on the sprocket sleeve 163 (Fig. 16). The motor and directly connected parts may be mounted on a platform 196 secured to the sub-base.

When the clutch 165 is engaged, the rotation of the sprocket 199 will cause rotation of the

shaft 158 and the latter will drive the shaft 176 through the sprockets 161 and 178 and the connecting chain 182. The shaft 176 causes rotation of the shaft 177 through the meshing gears 179 and 184. Similarly rotation of the shaft 158 causes rotation of the shaft 171 through the gears 159 and 170.

The bevel gear 160 of the shaft 158 meshes with the bevel pinion 200, and thus drives the shaft 126, and the latter through the bevel pinions 125 and 124 drives the stub shaft to which is attached the pinion 120. The latter drives the spot sealer and the side seam sealer.

The rotation of the shaft 171 with its bevel pinion 175 causes rotation of the shaft 202, and the latter through the various bevel gears shown in Fig. 3 rotates the shaft 153 of the transverse seam sealer and the shaft 206 which operates the shaft 73 of the feed roller 71.

Thus all of the operating parts are driven in proper synchronism, and by the proper selection of pitch diameters for the gears and sprockets and the proper selection of the diameters of the various rotatable operating units, the three webs are drawn into the machine, the webs B—C are pasted together, the web A is brought to channel-shaped form, the web B is spot sealed to the in-turned edges of the channel, the transverse pleats are formed in the laminated web B—C, the side edges of the web B are secured by continuous seams to the edges of the channel web A to form a tube, the side walls of the tube are tucked in, the bag is collapsed to expel air therefrom, the bag is sealed transversely at spaced points along the length, and the completed collapsed sealed bags are severed by cutting intermediate of the edges of each transverse sealed area and are delivered from the machine. All of the operations are performed in the proper sequence and from a single drive so that all of the parts and steps are kept in proper synchronism and the machine when started will run continuously without manual control or manual operation of any of the parts.

In the specific construction of bag produced by the machine above described only one side will be opaque due to the web C of paper or other non-heat sealable material. In some cases it is desirable to reinforce or cover all four sides of the final bag by non-heat sealable and possibly relatively opaque material. In Figs. 26 to 28 I have shown a modification of the machine which permits this to be done. The main frame of the machine is provided with an auxiliary frame 210 serving to support a roll D of paper or other similar material, and the roll A is supported on a bracket 211 on the main frame. This bracket also supports a glue pot 212, and the paper passes over idler rollers 213 and 214 to a roller 215 juxtaposed to a glue roller 216. The surface of the paper is thus covered with adhesive and after leaving the roller 215 it is brought in surface contact with the web A as the two sheets pass over an idler roller 217 on the way to the roller 56 of the main body of the machine.

In some cases it is desirable that the opaque web D be provided with a window d¹ through which the contents of the bag may be viewed, and with windows d² registering with the end of the bag to be formed. These are shown in Fig. 29. Any suitable punching mechanism may be employed for producing these apertures. As shown, the web D passes over a templet plate 218 and above this is a punching plate 219 guided on vertical rods 220 and actuated by links 221. The

latter may have eccentric straps at their lower ends engaging an eccentric 222 which causes the up and down movement of the punching plate.

As the web must be punched while traveling, it is desirable that the punch plate and templet plate move back and forth in the direction of travel of the sheet material. For this purpose the templet plate which carries the guide rods 220 may itself slide on horizontal guide rods 223 and may have a depending roller 224 engaging a cam groove in a cam 225. The latter may be actuated by spiral gears from the shaft 226 which drives the shaft 228 carrying the eccentrics, by means of gears 227. The timing and the shape 15 of the cam groove in the cam 225 are such that while the punch is passing through and back out of the paper the templet plate and punch will be traveling with the paper and at the same speed. When the punch rises above the paper 20 the cam carries the templet plate and punch in the opposite direction, and the direction of movement is again reversed before the punch enters the paper the next time. The timing is also such that the openings d^1 and d^2 will be formed at 25 points spaced apart along the length of the web D corresponding to the length of the completed bag which is to be produced. Of course, the driven parts of this mechanism must be in proper timed relationship to the remainder of the machine. As shown a chain 230 driven from a 30 sprocket on the shaft 158 may extend around sprockets on the roller 215 and the shaft 226 to drive these and to also time them with the other operations.

To get the proper timing of the punching mechanism the sprocket 231 may be made circumferentially adjustable in respect to the shaft 226. To prevent the punches from lifting the web off the templet plate when the punches rise 40 out of the sheet, there may be provided a stripper plate 232 spaced from the templet plate to provide a thin passage for the web D.

The conveyer for the completed bags and which is somewhat diagrammatically illustrated in Fig. 45 26 and between the glue pot 212 and the shaft 181, is somewhat different in detail from that shown in Fig. 2, but as such details do not constitute any portion of my present invention further description appears to be unnecessary.

It will be understood that the web D is slightly 50 narrower than the web A so that the web D will be folded to channel shape, but will be turned in to a limited extent to abut but not overlap the edges of the web B. Thus the heat sealable material A will come in contact with and be sealed to the surface of the heat sealable material of the web B, and the edge portions of the web C to which adhesive has been applied may be glued to the edges of the web D.

By the use of features illustrated in Figs. 26 to 28 and used in connection with the main features of the machine first described, a bag may be produced which will be completely lined with heat sealable material, but all walls will be laminated and the outer surface will be protected by the paper or other analogous sheet material not adapted for direct heat sealing. The slots d^2 are so positioned that they leave exposed strips across the infolded side walls of the tube, and thus the four superposed layers of the heat sealable material may all be sealed together by the sealers 160. The transverse cutter 168 operates to sever the bag intermediate of the edges of the openings d^2 where the transverse seam has been made.

The construction and method illustrated in Figs. 26 to 29 inclusive in which the infolded walls are laminated and the outer lamination is so formed as to permit the direct sealing together of the inner laminations of the infolded portions in narrow transversely extending areas, is claimed in my divisional application 329,422, filed April 13, 1940.

Having thus described my invention, what I claim as new and desire to secure by Letters Patent is:

1. An apparatus for forming a tube of flexible material, including means for delivering a web of material and progressively folding it to substantially channel shape rectangular in cross-section with inturned marginal portions, and a pair of opposed rollers, one within said tube and beneath said marginal portions for progressively securing the edges of a second web to said marginal portions. 15

2. An apparatus for forming a tube of flexible material, including means for delivering a web of material and progressively folding it to substantially channel shape rectangular in cross-section with inturned marginal portions, means 25 for progressively securing the edges of a second web to said marginal portions, and means for thereafter progressively infolding the side walls of the channel-shaped web to collapse the tube and expel air therefrom. 30

3. An apparatus for forming a tube of flexible material, which includes means for progressively advancing two webs of sheet material at different rates of travel, and means for forming transverse pleats in one of said webs along lines spaced 35 apart lengthwise of the web.

4. An apparatus for forming a tube of flexible sheet material, which includes means for progressively advancing two webs of sheet material lengthwise in superposed positions but at different rates of speed, and means for securing together the marginal edges of the two webs at spaced points. 40

5. An apparatus for forming a tube of flexible sheet material, which includes means for progressively advancing two webs of sheet material lengthwise in superposed positions but at different rates of speed, means for securing together the marginal edges of the two webs at spaced points, and means for forming transverse pleats 50 in the faster traveling web between successive spaced points. 45

6. An apparatus for forming a tube of flexible sheet material, including means for advancing a web and progressively folding it to substantially channel shape, means for advancing a second web at a faster rate, means for sealing the edges of the second web to the edges of the first web at spaced points along the length thereof, and means for folding down excess material 60 of the second mentioned web adjacent to each of said points to form transverse pleats. 55

7. An apparatus for forming a tube of flexible sheet material, including means for advancing a web and progressively folding it to substantially channel shape, means for advancing a second web at a faster rate, means for sealing the edges of the second web to the edges of the first web at spaced points along the length thereof, means for folding down excess material of the second 70 mentioned web adjacent to each of said points to form transverse pleats, and means for thereafter sealing together the edges of the webs between said pleats and the next sealing points to form a tube completely closed along the edges 75

of the webs but with transverse pleats in the second mentioned web.

8. An apparatus for forming a tube of flexible sheet material, including means for advancing a pair of webs at different rates of speed and with the edges of one juxtaposed to the edges of the other, means for spot sealing the edges together at points spaced along the length thereof, and means for forming pleats in the faster traveling web and overlying the spot seals.

9. An apparatus for forming collapsed sealed bags, which includes means for advancing a pair of webs with opposite edges juxtaposed, means for sealing together said juxtaposed edges to form a tube, means for sealing the webs together transversely of the tube along lines spaced apart lengthwise of the tube, and means for severing the tube into sections along lines intermediate of the edges of the transverse sealed portions to form collapsed bags sealed across both ends.

10. An apparatus for forming collapsed sealed bags, including means for progressively advancing a web of sheet material and bending it to substantially channel form, means for advancing a second web at a higher rate of speed with its edges juxtaposed to the edges of the first mentioned web, means for spot sealing the juxtaposed edges together at points spaced along the length thereof, means for folding over the excess material of the second mentioned web to form pleats overlying the spot seals, means for sealing together the remaining portions of the juxtaposed edges to form a tube, means for infolding the side edges of the channel shaped web to collapse the tube, means for sealing together the two webs along transverse lines spaced apart lengthwise of the tube, and means for severing the tube along transverse lines intermediate of the edges of the transverse sealed portions to form collapsed sealed bags.

11. An apparatus for forming a collapsed tube of sheet material, including a mandrel substantially rectangular in cross-section, means for advancing a web of sheet material and folding it to substantially channel shape around said mandrel and with infolded marginal edges, means for delivering a second web along said mandrel with its edges superposed to said infolded edges, an a sealing device including a rotor supported by and disposed within said mandrel and a second rotor cooperating with the first one and having annular heated flanges cooperating with said first mentioned rotor for sealing together said superposed edges.

12. An apparatus for forming a collapsed tube of sheet material, including a mandrel substantially rectangular in cross-section, means for advancing a web of sheet material and folding it to substantially channel shape around said mandrel and with infolded marginal edges, means for delivering a second web along said mandrel at a higher rate of speed with its edges superposed to said infolded edges, and a sealing device including a rotor having heated flanges for pressing the superposed edges together at spaced points to form spot seals.

13. An apparatus for forming a collapsed tube of sheet material, including a mandrel substantially rectangular in cross-section, means for advancing a web of sheet material and folding it to substantially channel shape around said mandrel and with infolded marginal edges, means for delivering a second web along said mandrel at a higher rate of speed with its edges superposed to said infolded edges, a sealing device including a

rotor having heated flanges for pressing the superposed edges together at spaced points to form spot seals, and means beyond said sealing means for folding the excess material of the second mentioned web into a pleat overlying the 5 spot seals.

14. An apparatus for forming a collapsed tube, including a mandrel, means for delivering web material along opposite sides of the mandrel with the edges of the material juxtaposed, means for heating and pressing together the juxtaposed edges to form the tube closed along its sides, tuckers disposed beyond said mandrel for infolding portions of the walls of the tube to collapse the latter, and a drum around which the 10 collapsed tube passes.

15. An apparatus for forming a collapsed tube, including a mandrel, means for delivering web material along opposite sides of the mandrel with the edges of the material juxtaposed, means for 20 heating and pressing together the juxtaposed edges to form the tube closed along its sides, tuckers disposed beyond said mandrel for infolding portions of the walls of the tube to collapse the latter, a drum around which the collapsed tube passes, and a member movable along an arcuate path substantially parallel to the surface of the drum and coacting with said drum to apply heat and pressure to the collapsed tube 25 transversely thereof to form transverse sealed 30 areas.

16. An apparatus for forming a collapsed tube, including a mandrel, means for delivering web material along opposite sides of the mandrel with the edges of the material juxtaposed, means for 35 heating and pressing together the juxtaposed edges to form the tube closed along its sides, tuckers disposed beyond said mandrel for infolding portions of the walls of the tube to collapse the latter, a drum around which the collapsed 40 tube passes, a member movable along an arcuate path substantially parallel to the surface of the drum and coacting with said drum to apply heat and pressure to the collapsed tube transversely 45 thereof to form transverse sealed areas, and a cutting mechanism disposed beyond said drum for cutting the tube into successive sections along lines registering with said transverse sealed areas.

17. Apparatus for forming a tube including 50 means for progressively advancing and adhesively securing together a web of heat sealable material and a web of non-heat sealable material, means for progressively advancing a second web of heat sealable material, a pair of coacting elements for applying heat and pressure to the edges of the heat sealable materials to form longitudinal seams, and a second pair of coacting elements for pressing together the sheets of heat sealable material to form transverse seams.

18. The method of forming a tube, which includes advancing a web of sheet material and progressively folding it to channel shape, advancing a second web with its edges juxtaposed to the edges of the first mentioned web, progressively sealing said edges together as the webs advance, thereafter infolding portions of the walls of the tube to progressively collapse the latter, and sealing the webs together along transverse lines spaced apart lengthwise of the webs.

19. The method of forming a tube with transverse pleats on one wall thereof, which includes advancing a pair of webs at different rates of speed and with the edges juxtaposed, forming transverse pleats in the web traveling at the 75

higher speed, and progressively sealing together the edges of the webs.

20. The method of forming a tube with transverse pleats across one wall thereof, which includes progressively advancing a pair of webs at different speeds and with the edges juxtaposed, spot sealing the edges together at spaced points, forming pleats in the web traveling at the higher speed and adjacent to each spot seal, and thereafter sealing together the edges of the webs between the pleat and the next spot seal.

21. The method of forming a tube with transverse pleats, which includes progressively advancing a pair of webs at different speeds, forming transverse pleats in the web traveling at the higher speed, and progressively sealing together the edges of the webs.

22. The method of forming a tube with transverse pleats, which includes progressively advancing a pair of webs at different speeds, forming transverse pleats in the web traveling at the higher speed, progressively sealing together the edges of the webs, and thereafter sealing the webs together along transverse spaced lines.

23. The method of forming a tube with transverse pleats, which includes progressively advancing a pair of webs at different speeds, forming transverse pleats in the web traveling at the higher speed, progressively sealing together the edges of the webs, thereafter sealing the webs together along transverse spaced lines, and thereafter subdividing the tube transversely into sections along lines spaced a predetermined distance from the successive transverse pleats.

24. The method of forming a tube with transverse pleats, which includes progressively advancing a pair of webs at different speeds, forming transverse pleats in the web traveling at the higher speed, progressively sealing together the edges of the webs, thereafter sealing the webs together along transverse spaced lines, and thereafter subdividing the tube transversely into sections along lines intermediate of the edges of the transverse seals.

25. The method of forming completely sealed bags in collapsed condition, which includes progressively sealing together the edges of a pair of webs, infolding portions of the side walls of the resulting tube, pulling the tube around a curved surface to expel air from the interior of the tube, transversely sealing together the opposite walls of the tube while in collapsed condition, and thereafter subdividing the tube into sections along lines intermediate of the opposite edges of the transverse seals.

26. The method of forming a tube with transverse pleats, which includes delivering a pair of webs in superposed relationship and at different rates of speed, forming transverse score lines in one of the webs at spaced points along the length thereof, and folding the material of the last mentioned web along said score lines to form successive transverse pleats.

27. An apparatus for forming a collapsed tube, including a mandrel, means for delivering web material along opposite sides of the mandrel with the edges of the material juxtaposed, means for heating and pressing together the juxtaposed edges to form the tube closed along its sides, a drum around which the collapsed tube passes, and a member movable along an arcuate path substantially parallel to the surface of the drum and coating with said drum to apply heat and

pressure to the collapsed tube transversely thereof to form transverse sealed areas.

28. An apparatus for forming a collapsed tube, including a mandrel, means for delivering web material along opposite sides of the mandrel with the edges of the material juxtaposed, means for heating and pressing together the juxtaposed edges to form the tube closed along its sides, a member presenting a curved surface and around which the collapsed tube passes, and a member cooperating with said first mentioned member and presenting a surface movable in engagement with the surface of the tube and at the same speed as that of the tube to apply heat and pressure to the collapsed tube to form a seal.

29. An apparatus for forming a collapsed tube, including a mandrel, means for delivering web material along opposite sides of the mandrel with the edges of the material juxtaposed, means for heating and pressing together the juxtaposed edges to form the tube closed along its sides, a member having a curved surface around which the collapsed tube passes, said member presenting a resilient surface, and a second member cooperating with the first member to press superposed layers of the tube together and to apply heat and pressure to form a seal.

30. An apparatus for forming a tube, including means for progressively advancing and adhesively securing together a web of heat sealable material and a web of non-heat sealable material, means for progressively advancing a second web of heat sealable material, and a pair of coating elements for applying heat and pressure to the edges of the heat sealable materials to form longitudinal seams, one of said elements having a resilient surface, and both of said elements having rolling contact with said material.

31. An apparatus for forming collapsed sealed bags, which includes means for advancing a pair of webs with opposite edges juxtaposed, means for sealing together said juxtaposed edges to form a tube, means for collapsing said tube, means for thereafter sealing the webs together transversely of the tube along lines spaced apart lengthwise of the tube, and means for thereafter severing the tube into sections.

32. An apparatus for forming a collapsed tube of sheet material, including a mandrel substantially rectangular in cross-section, means for advancing a web of sheet material and folding it to substantially channel shape around said mandrel and with infolded marginal edges, means for delivering a second web along said mandrel with its edges superposed to said infolded edges, and a sealing device including a rotor supported by and disposed within said mandrel and annular heated flanges cooperating with said rotor for sealing together said superposed edges.

33. An apparatus for forming collapsed sealed bags, which includes means for advancing a pair of webs with opposite edges juxtaposed, one of said webs comprising heat sealable material and the other including heat sealable material and an outer protecting layer, means for applying heat and pressure through the protecting layer to seal together said juxtaposed edges to form a tube, means for thereafter infolding opposite side walls of said tube, means for applying heat and pressure to seal the webs together with the infolded sides therebetween and along transverse lines spaced apart lengthwise of the tube, and means for severing the tube into sections.
